UNITED STATES PATENT OFFICE.

FREDERICK J. KALDENBERG, OF NEW YORK, N. Y., ASSIGNOR TO THE NOVELTY MANUFACTURING COMPANY, OF WATERBURY, CONNECTICUT.

DESIGN FOR A CANE OR UMBRELLA HEAD.

SPECIFICATION forming part of Design No. 15,849, dated February 17, 1885.

Application filed September 25, 1884. Term of patent 7 years.

To all whom it may concern:

Be it known that I, FREDERICK J. KALDENBERG, of the city and State of New York, have invented a Design for the Heads of Canes, Umbrellas, &c., of which the following is a specification.

This design for a cane, umbrella, or parasol head consists of a sphinx, *a*, at one end of the cane-head, from which extends a body and tail. The head has the hood *i* at the sides and back, with ribs and intermediate corrugated panels. The upper part of the body is a gradual curve at *b*, increasing in sharpness and turning downwardly and forward at *c* to form the tail, and the under part of the body and tail is a compound curve at *d*, extending downwardly to the circular connection at *e*,

that coincides with the stick or cane. The general configuration of the body is circular in cross-section at the line *xx*. The body and tail portion is shown as with scales; but these may be omitted.

I claim—

The design for a cane or umbrella head, consisting in the sphinx head and hood and the body portion and curved tail, and the imitation of scales, substantially as set forth.

Signed by me this 20th day of September, A. D. 1884.

F. J. KALDENBERG.
